CLAIM

The ornamental design for a keyboard dock as shown and described.

DESCRIPTION

FIG. 1 is a top, front and right side perspective view of a keyboard dock showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is a top, front and right side perspective view of the keyboard dock of FIG. 1, shown installed on an environmental keyboard.

The broken lines in FIG. 8 showing the additional keyboard structure depict environmental subject matter only and form no part of the claim, while all other broken lines depict portions of the keyboard dock that form no part of the claimed design.

1 Claim, 5 Drawing Sheets(56)
